UNITED STATES PATENT OFFICE.

BERT D. GILSON, OF CHICAGO, ILLINOIS.

ENGINE STARTER.

Application filed December 8, 1921. Serial No. 521,026.

To all whom it may concern:

Be it known that I, BERT D. GILSON, a citizen of the United States, residing at Chicago, in the county of Cook and State 5 of Illinois, have invented new and useful Improvements in Engine Starters, of which the following is a specification.

This invention relates to automatic means for transmitting rotations of a prime mover 10 to a driven member of an engine for the purpose of starting such engine; and it has primarily in view the starting of an internal combustion engine, such as used in self propelled vehicles.

15 In the year 1884 a British patent issued to Galloway for an engine starting device comprising a screw rotatable by a prime mover, and a pinion rotatable on the threads of this screw for advance into engagement 20 with a driven member of the engine. The pinion apparently was manually advanced into engagement with said driven member, whereupon rotation of a screw transmitted rotations to the said driven member, 25 through the medium of the pinion, thereby throwing the engine over the dead center and permitting it to start. Once started it was found that the driven member attained much higher speed than the screw (which 30 moreover supposedly would be stopped immediately its function was performed) causing the pinion to be thrown out of engagement with the driven member. Various attempts have since been made to 35 cause such pinion to advance automatically on such screw for the purpose of starting internal combustion engines, the theory on which such attempts were based being, that the inertia of the pinion on the screw, the 40 moment the latter commenced to revolve, would be sufficient to cause the pinion to start to rotate more slowly, as a result of which the pinion would be compelled to advance axially on the screw into engagement 45 with the driven member of the engine. But it has been found that the friction between the pinion and screw is great enough to 50 overcome the inertial retarding tendency of the pinion, and various devices, such as counterweights and resilient friction devices, have been resorted to for the purpose of maintaining the pinion unturned during its 55 advance into engagement with the driven member of the engine.

The general object of this invention is to provide a structure in which a pinion is automatically advanceable without resorting

to such retarding devices. A further object is the provision of resilient means, commencing to function the moment the pinion begins to engage the driven member of the 60 engine and forming a flexible driving connection between the screw and pinion. The further objects and features of importance of my invention will appear and readily be comprehended upon perusal of the following description, and by referring to the accompanying drawing, of which:

Fig. 1 is a side elevation of portions of an internal combustion engine embodying the invention; Fig. 2 shows on a larger scale 70 the portion of the engine supporting the starting device, which latter is shown substantially in section through its center; Fig. 3 is a similar view showing the device in its advanced position and in the act of 75 rotating the engine fly wheel for the purpose of starting the engine; Fig. 4 is a view substantially in agreement with Fig. 3, but showing the device again retracted.

The numeral 1 denotes an internal combustion engine, and 2 is the engine crank-shaft, to which is rigidly secured a fly wheel 3. On the periphery of this fly wheel is placed an annular toothed gear 4, into mesh with which a pinion 5 is mounted to 80 advance. The pinion is fitted to rotate on a shaft 6 of a prime mover 7, which latter is preferably an electric motor such as commonly employed for the purpose of starting internal combustion engines. The rear end 90 of the pinion is much enlarged in diameter, and screw-threads 5^a are cut into the peripheral surface of this enlarged portion of a size to mesh with internal screw threads 8^a of a cylindrical housing 8, which latter 95 in turn is rigidly secured to the starting motor-shaft 6, as by a pin 9. It is now noticed that only the rear portion of the pinion perforation rides directly on the motor shaft. The greater part of this perforation is counter-bored to a larger diameter in order to provide a cylindrical chamber 5^b of a size to accommodate a powerful 100 spring 10. The front end of the pinion rides on a sleeve 11, which is suitably fastened to the motor shaft, and this sleeve is made with an enlarged portion 11^a fitted to rotate in a bearing portion 7^a of the motor casing 7. Or the sleeve may be integral with the shaft if so desired.

105 The foregoing description is sufficient to show the operation of the device. When the circuit through the motor is closed, the

motor shaft is forced to rotate, carrying with it the housing 8, but the pinion 5 is free on the shaft, and the slight friction between the pinion and the shaft is not sufficient to overcome the inertia which tends to maintain the pinion unturned. But as the pinion threads 5^a are in engagement with the threads 8^a of the revolving housing it follows that the pinion must advance into mesh the fly wheel gear 4. Now it may be suggested that the combined friction between pinion and shaft and pinion threads with the housing threads will suffice to overcome the inertia of the pinion, but such is not the case, although it is found to be so in the type of drive hereinbefore referred to, in which the pinion is made with internal screw threads riding on screw threads of the motor-shaft. There are various reasons for this apparent inconsistency, as will be appreciated by those versed in the laws of physics and mechanics. Without stating any particular rule, such as may be applied to each specific structure, it is sufficient to say that the smaller the friction surface between the pinion and shaft, the less friction is encountered, and that very little friction surface remains in the structure of Fig. 2. At the same time it will also be noticed that the pinion is well supported in its advanced position, as indicated in Fig. 3, so that the strength needed for driving purposes is not sacrificed when the pinion is advanced to turn the fly wheel. A second reason is, that the further the screw-threads are removed from the axis of the shaft, the less the friction load. A third reason is that, assuming the same lead in all cases, then the further the screw-threads are removed from the axis, the easier the angle of the thread helix hence the less the angular friction during the axial advance movement of the pinion. There is then a point at which the inertia of the pinion becomes greater than the friction load. That point is reached where the diameter of the screw threads is about four times the diameter of the shaft, if the pinion is four times the length of the shaft diameter and is fitted to bear on the shaft, the full length of the pinion. But as the pinion, in the structure of my invention, only has sufficient bearing on the shaft to support its own weight, in its retarded position, it is found that the diameter of the screw threads need only be about twice the diameter of the shaft. And this relation is substantially indicated in the drawing.

The spring 10 performs very important functions. It is not merely a buffer, but it forms a means of maintaining the pinion floating on the shaft, as will appear presently. Let it be assumed that the pinion has advanced into engagement with the fly wheel gear. Meeting the resistance of the latter it must continue to advance until

the force required to compress the spring becomes greater than the resistance of the fly-wheel, whereupon the latter commences to turn, thereby relieving the pressure on the spring, which commences to expand and to push the pinion back or to speed up the fly-wheel. If now one or more cylinders are on the compression stroke it is found that the resistance of the fly-wheel will increase rapidly, causing the pinion to move forward and possibly entirely to compress the spring. When the cylinder compression stroke is completed there is a sudden drop in the resistance resulting in a repulsion of the pinion and a speed acceleration of the fly-wheel. Thus it is seen that power is stored in the spring while the fly-wheel resistance increases, and that this stored power is utilized to accelerate collapses. Furthermore that the pinion is in a constant state of axial movement during the starting operation, in other words that it floats. The advantage of the floating pinion is that the wear on the pinion and fly-wheel gear is distributed over the entire surface of these parts, whereas in the starting devices now in use the wear always occurs in the same place, thereby shortening the life of the parts. The spring 10 should occupy nearly the entire space within the pinion, leaving only sufficient freedom for the pinion to move forward to touch the fly-wheel before the compression of the spring commences.

It happens occasionally that vibrations of the running engine cause the pinion to advance until it touches the fly-wheel gear, which then instantly throws the pinion back. This is not of any great consequence, except that it subjects the parts to undue wear, and also that the noise of such collision is objectionable. It is desired to introduce means tending to maintain the pinion retracted, when not in use, and such means may take the shape of a slight drop 11^b of the peripheral front end surface of the sleeve 11. Such drop must, of course, be extremely slight and gentle, in order not to form a positive obstruction to the desired advance of the pinion, and it has been much exaggerated in the Fig. 2 of the drawing in order to make the drawing more readily readable. Or it may consist in the introduction of a very sensitive spring 12 urging the pinion into retracted position, and yet not strong enough to interfere with the desired advance movement when the motor is started. This spring is indicated in Fig. 3, and it is shown fully compressed. When it expands, and the pinion is fully retracted, it occupies the entire length of the space within the pinion.

I claim:

1. In an engine starter, an engine driven member, a motor driven shaft, an internally threaded housing on the shaft, a pinion bear-

ing on the shaft and normally within said housing, said pinion having a threaded enlargement engaging the housing threads for projecting the pinion axially on the shaft 5 out of the housing and into engagement with said engine driven member, a resiliently compressible member within said pinion and opposing the advance of the pinion after reaching said engine driven member, and means 10 for yieldingly maintaining the pinion in retracted position.

2. In an engine starter, a driven member of the engine, an electric motor, a rod at-

tached to the end of the motor shaft, a cylindrical housing covering the outer end 15 of said rod, a member normally within said housing and interconnected therewith to be axially advanced thereby on the rod, when the rod and housing commence to rotate, into engagement with said driven member, and 20 means within said enclosed member yieldingly opposing further advance of the enclosed member.

In testimony whereof I have hereunto affixed my signature.

BERT D. GILSON.
